UNITED STATES PATENT OFFICE.

ROSALIE K. HEYMAN, OF NEW YORK, N. Y., ASSIGNOR OF ONE-HALF TO OSCAR HEYMAN & COMPANY, OF NEW YORK, N. Y., A COPARTNERSHIP.

DESIGN FOR A BOTTLE.

No. 37,579.

Specification for Design.

Patented Oct. 24, 1905.

Application filed August 16, 1905. Serial No. 274,477. Term of patent 7 years.

To all whom it may concern:

Be it known that I, ROSALIE K. HEYMAN, a citizen of the United States, residing in the city, county, and State of New York, have invented a new, original, and ornamental Design for a Bottle, of which the following is a specification, reference being had to the accompanying drawing, forming a part thereof.

The figure is a perspective view showing my new design.

I claim—

The ornamental design for a bottle as shown.
ROSALIE K. HEYMAN.
